UNITED STATES PATENT OFFICE.

WINFIELD S. LIVENGOOD, OF KANSAS CITY, MISSOURI, ASSIGNOR TO THE SMITH & SONS MANUFACTURING COMPANY, OF KANSAS CITY, MISSOURI, A CORPORATION.

WHEELED SCRAPER.

SPECIFICATION forming part of Letters Patent No. 694,561, dated March 4, 1902.

Application filed September 7, 1901. Serial No. 74,687. (No model.)

To all whom it may concern:

Be it known that I, WINFIELD S. LIVENGOOD, a citizen of the United States, residing at Kansas City, in the county of Jackson, in the State of Missouri, have invented certain new and useful Improvements in Wheeled Scrapers, of which the following is a full, clear, and exact description, reference being had to the accompanying drawings, which form a part of this specification.

My invention relates to certain new and useful improvements in wheeled scrapers, having more particular relation to the application of the draft appliances to the scraper-pan and also to the construction and arrangement of the brace-bar by which the rear of the scraper-pan is connected with the axle. Heretofore in scrapers of this type in which the scraper-pan is hung by a bail from the axle the draft-bars have been connected with the axle in such manner that the draft is applied to the axle and thence through the bail to the scraper-pan. In such construction when the scraper-pan is let down to take its load it hangs at a considerable distance below the axle and below the point of direct application of the draft, and the point of connection of the bail with the scraper-pan is to the rear of the point of application of the draft. The draft is thus applied at a very great disadvantage and has no tendency or at most very little tendency to draw the scraper-pan into the soil. It hence requires very arduous labor on the part of the operator, usually two men being required to hold the scraper-pan in position to take its load. With my improvements by connecting draft-bars with the bail in such manner that the draft is applied directly to the scraper-pan and in such relation that the scraper-pan is drawn into the soil, whereby the arduous labor is very much relieved, in so much, indeed, that one man may easily operate the scraper, even to the extent of causing the pan to enter the soil below where it may have been previously plowed, which before could scarcely be done by two men.

To accomplish this and other objects, as will appear, my invention consists in certain features of novelty hereinafter described, and set out in the claims.

Figure 1 represents a plan view of a wheeled scraper embodying my invention and improvements. Fig. 2 represents a plan view, somewhat enlarged, of a scraper, partly broken away, showing more in detail the draft appliances and the folding rear brace-bar. Fig. 3 represents a side elevation showing the draft appliances from the inner side, the view being taken substantially on the line xx of Fig. 60. Fig. 4 represents a side elevation of the scraper. Fig. 5 represents a detail view showing the manner of connecting the draft appliances with the scraper. Fig. 6 represents a detail view of the hanger by which the bail and push-bars are supported from the axle. 65

Similar numerals refer to similar parts throughout the several views.

1 represents the wheels, and 2 an arched axle of the usual construction. Upon said axle are mounted hanger-blocks 3, carrying a hanger 4, which are formed by forwardly-extending arms 5, on which are provided pockets 6 by inner flanges 6^a. In said pockets are seated the push-bars 7 and the bail 8, 75 said push-bars being rigidly secured to said arms 5 and said bail being pivotally mounted in said pocket. By this construction a very great advantage is gained in that in the usual construction the bail and the bars 7, 80 which in such usual construction are the draft-bars, are connected to the arm simply by passing bolts through the same and through the arms 5, and said bolts not being supported at the inner ends the weight and pull of the 85 scraper when at work tends soon to loosen the bolts and cause objectionable loosening and disorganization of the parts, while by seating the bail and bars in the pocket and passing the bolt through the inner flange the 90 bolt is supported at both ends, and such objectionable loosening is avoided and the structure strengthened at a weak point.

The push-bars 7 extend forward and are connected with the draft pole or tongue 9 and a platform 10, mounted thereon, as in the usual construction. The bail is also pivotally connected with ears 11 on the scraper-pan in the usual manner. Upon said bail are mounted yokes 12, said yokes extending a 100 substantially equal distance on each side of the pivotal point of the bail upon the hanger.

Upon said yokes are mounted the draft-bars 13, the point of connection of said draft-bars with the yokes being to the rear of the pivotal point or fulcrum of the bail on the hang- 5 ers, the relation being such that as the scraper-pan is let down to take its load said point of connection will pass from above to below the fulcrum of the bail, and as the loaded scraper is raised said point will pass from 10 below to above the fulcrum. The effect of this is that when the scraper is let down to take its load the draft being exerted on the bail between its fulcrum and the scraper-pan acts with a very great leverage to draw the 15 pan into the soil, so much so that it will cut into and enter the soil below where it has been previously plowed, cutting to some depth below the level of the wheels, as shown in Figs. 3 and 4.

20 The draft-bars are connected with a draft-beam 14, suspended by links 15 from the platform, and said draft-beam is connected by draft-rods 16 with the doubletree 17, which is carried upon a bolt 18, which works in a slot 25 19 in the tongue, so that as the scraper-pan is raised and lowered the doubletree is permitted a longitudinal movement to accommodate the movement of the pan.

The bail is provided with the usual hand- 30 lever 20, by which the scraper-pan is raised and lowered, and the usual spring-catch 21 is mounted upon the platform and arranged to engage said lever to retain the scraper-pan in elevated position. In Fig. 3 the parts are 35 shown in heavy lines with the pan lowered to take its load and in dotted lines with the pan elevated to carry its load.

A brace-bar 22 is provided between the axle and the platform to retain the axle in 40 vertical position.

The rear of the scraper-pan is supported by a folding brace or stay-bar of peculiar construction, consisting of a bar 23, pivotally mounted between ears 24 on the pan, and bars 45 25, pivotally connected with the axle, said bars being hinged together at 26, so that when the scraper-pan is turned up in position to travel upon the road said bars will be folded together, as shown in Fig. 4, a hook 27 being 50 provided and arranged to engage the rod 36 at the rear of the pan upon which the bar 23 is mounted and retain the pan in position when turned up, said rod also extending beyond the ears to form a handle 36^a, by which 55 the rear of the pan is lifted up. An extension 28 is provided upon the bar 23, and a stirrup 29 is mounted upon the bars 25 and arranged to be turned over said extension and lock the bars against folding when the 60 scraper-pan is carried in operative position, as shown in Fig. 3.

Upon the axle between the hanger-blocks 3 and the wheel-hubs are mounted caps 30, bearing against said blocks and provided with 65 sleeves 31, embracing the axle and having lugs 32 at the outer ends, and caps 33, bearing against the wheel-hubs, are provided with

sleeves 34, telescoping said sleeves 31 and having a recess 35, arranged to be engaged by said lugs, whereby is provided a very convenient and effective construction to retain the wheels in proper position upon the axle. 70

The draft being applied directly to the scraper-pan, it is manifest that the wheels and axle or frame of the machine are pushed forward by the connection of the bail with the push-bars 7.

Having thus fully described my improvements, what I claim as my invention, and desire to secure by Letters Patent, is— 80

1. In a wheeled scraper having its pan carried by a bail suspended from the axle, the draft appliances connected with said bail, whereby the draft is applied with a leverage upon said bail to draw the pan into the soil 85 in taking its load; substantially as set forth.

2. In a wheeled scraper having its pan carried by a bail suspended from the axle, yokes on said bail, and draft-bars connected with said yokes and with the doubletree; substan- 90 tially as set forth.

3. In a wheeled scraper having its pan carried by a bail suspended from the axle, yokes having their ends mounted upon said bail upon opposite sides of the points of suspen- 95 sion, and draft-bars connected with said yokes to the rear of said points of suspension, and with the doubletree; substantially as set forth.

4. In a wheeled scraper having its pan carried by a bail suspended from the axle, yokes having their ends mounted upon said bail upon opposite sides of the point of suspen- 100 sion, and draft-bars connected with said yokes and with the doubletree, and arranged in such 105 manner as to pass the point of suspension as the pan is raised and lowered; substantially as set forth.

5. In a wheeled scraper having its pan carried by a bail suspended from the axle, the 110 combination substantially as described, of the push-bars connected with the axle and with the scraper-tongue, a platform mounted thereon, a draft-beam suspended by links from said platform, yokes mounted upon the bail, draft- 115 bars connected with said yokes and with said draft-beam, a doubletree slidably mounted upon the scraper-tongue, and draft-rods connected with said draft-beam and with said doubletree. 120

6. In a wheeled scraper, the combination of an arched axle upon which the wheels are mounted, hanger-blocks mounted upon the axle, arms on said blocks provided with inwardly-arranged pockets, push-bars mounted 125 upon said arms, a bail mounted in said pockets, and a scraper-pan carried by said bail, and draft appliances connected with said bail; substantially as set forth.

7. In a wheeled scraper, the combination 130 with an arched axle upon which the wheels are mounted, hanger-blocks mounted upon said axle, arms on said blocks, and pockets on said arms formed by an inwardly-extend-

- ing portion provided with an upturned flange; substantially as set forth.
8. In a wheeled scraper having its pan carried by a bail suspended from the axle, a folding stay-bar pivotally connected at one end with the rear of the pan and at the other end with the axle, and a lock on said bar to prevent folding when the pan is down; substantially as set forth.
9. In a wheeled scraper having its pan carried by a bail suspended from the axle, hinged bars pivotally connected respectively with the rear of the pan and with the axle, and arranged to fold together as the scraper is turned up into traveling position, an extension on one of said bars, and a stirrup on the other bar arranged to engage said extension and lock said bars against folding when the scraper is down; substantially as set forth.
10. In a wheeled scraper the combination with the wheels and axle, of hanger-blocks mounted upon said axle, a sleeve on said axle provided with a cap bearing against said block, and a lug on the outer end of said sleeve, a sleeve on said axle telescoping with said aforementioned sleeve and provided with a cap bearing against the wheel-hub, and a recess in said sleeve arranged to be engaged by said lug on the other sleeve; substantially as set forth.
